SHEET SEPARATOR

Frank R. Belluche, Racine, Wis.

Application October 28, 1937, Serial No. 171,509

13 Claims. (Cl. 271—20)

This invention relates to improvements in sheet separators for sheet feeding machines of the type illustrated in Patent No. 2,075,016 issued to Elmer W. Belluche and Frank R. Belluche

5 March 30, 1937.

Many forms of sheet separators have been used in the past, but experience has shown that combing wheels combing the top of the pile or bank of sheets to buckle the same toward the mouths 10 of suckers, in general is the most satisfactory type of separator, especially for pile feeders of the type shown in the aforesaid patent.

In this type of separator as heretofore constructed, the combing wheels as well as the suckers were positively actuated to and from operative engagement with the pile of sheets. As a result, the combing wheels were in engagement with the top of the pile for a definite time interval which often was greatly in excess of the time 20 required to effect engagement between the suckers and the topmost sheet.

This condition was not conducive to high speed operation and had the added objection of marring delicately surfaced sheets through too 25 long an engagement of the combing wheels therewith.

With these and other objections to past and existing sheet separators in mind, it is an object of the present invention to provide a separator 30 mechanism wherein the combing wheel engages the pile of sheets for a time period only long enough to effect proper engagement of the mouths of the suckers with the topmost sheet.

Another object of this invention is to provide 35 a sheet separator wherein the lifting of the combing wheels off the topmost sheet is controlled by the sealing of the suction cups forming the mouths of the suckers by the sheet so that the sealing of each suction cup is accompanied by immediate lifting of its respective combing wheel.

Another object of this invention is to provide 40 pneumatic means for lowering the combing wheels into operative engagement with the top of the pile and to control the pneumatic means by the suction at the suction cups in such a manner that as long as the suction cups are open, the pneumatic means are operative and that upon sealing of the suction cups by the topmost sheet, 45 the pneumatic means are immediately rendered inoperative to release the combing wheels for lifting off the top of the pile.

Another object of this invention is to provide 50 means for coordinating the lowering of each combing wheel and its suction cup so that both

approach the top of the pile in unison while the combing wheel is free to be lifted independently of the suction cup.

Another object of this invention resides in the provision of a presser foot to engage the top of the pile of sheets, and toward which the combing wheel buckles the sheets, which presser foot is carried by the suction cup to move in unison therewith and so located that the suction cup is disposed between the presser foot and combing wheel.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed in accordance with the best mode so far devised for the practical application of the principles thereof, and in which:

Figure 1 is a perspective view with parts broken away and in section illustrating one entire sheet separating mechanism constructed in accordance with this invention;

Figure 2 is a side view of the separating mechanism showing the combing wheel and suction cup raised, and having parts thereof broken away and in section; and

Figure 3 is a top view of the mechanism with parts broken away and in section.

Referring now particularly to the accompanying drawings in which like numerals indicate like parts, the numeral 5 designates a combing wheel mounted to oscillate about a shaft 6 to and from operative engagement with the top of a pile of 40 sheets 7. The combing wheel may be of any desired design and construction and in the present instance is like that shown and described in detail in the aforesaid Patent No. 2,075,016.

Its shaft 8 extends through a tubular arm 9 which is fixed to a gear box 10 in which bevel gears (not shown) operate to provide a driving connection between the shaft 6 and the shaft 8 of the combing wheel. In this manner the combing wheel is constantly driven in a direction to 50 buckle the topmost sheets inwardly toward a presser foot 11.

The shaft 6 is journaled in bearings carried by brackets 12 which are slidably supported on a transverse bar 13 to enable sidewise adjust-

ment of the entire separating mechanism to accommodate sheets of different widths. The manner in which the shaft 6 is driven forms no part of this invention, suffice it to say that a suitable driving connection leads from the shaft 6 to a continuously driven part of the sheet feeding mechanism with which the separator is associated.

The presser foot 11 is clamped, as at 14, to the tube 15 of a sucker having a suction cup 16 mounted at its lower end. The upper end of the tube 15 has a suction line 17 attached thereto which leads to a suitable source of suction (not shown) through a cam controlled timing valve 18 diagrammatically illustrated in Figure 2.

The connected presser foot 11 and sucker are supported by levers 19 and 20 pivoted respectively on transverse supporting shafts 21 and 22. The lever 20 is medially supported from a cam 23 fixed to the shaft 6, by a cam roller 24 carried by the lever and riding on the cam. Being fixed to the shaft 6, the cam 23 rotates continuously to periodically raise and lower the lever 20 which is held down onto the cam by a tension spring 25. The lever 19 pivots about the shaft 21, and consequently, the raising and lowering of the lever 20 swings the suction cup upwardly and forwardly to lift and advance a sheet which it has picked up.

When the low part of the cam 23 passes under the roller 24, the suction cup and presser foot are lowered down onto the pile of sheets, as shown in Figure 1, with the presser foot slightly in advance of the suction cup so that upon buckling of the top sheets by the combing wheel toward the presser foot, they are raised toward the mouth of the suction cup 16.

A blower 26 is also provided to project a blast of air under the top sheet after it has been lifted and to also act as a presser foot. This blower is cam actuated in a manner somewhat similar to the actuation of the sucker and presser foot 11, but as this element does not form a direct part of the present invention, no further description thereof will be given. If desired, reference may be had to the aforesaid Patent No. 2,075,016 for its description.

The combing wheel 5 is biased to a raised position by a spring 27 hooked to the transverse shaft 21 and to a pin 28 mounted in a lug 29 formed on the tubular arm 9. Also attached to the pin 28 is a link 30, the upper end of which has an elongated slot 31 to receive a pin 32 fixed to the lever 20. This connection between the combing wheel and the suction cup insures simultaneous lowering of these elements onto the pile of sheets while allowing the combing wheel to be lifted by its spring 27 independently of the suction cup.

Acting in opposition to the spring 27 to lower the combing wheel into operative engagement with the pile of sheets is a pneumatic actuating means, indicated generally by the numeral 33. This actuating means comprises a cylinder 34 fixedly mounted in any suitable manner as by two supporting arms 35 and 36 which project rearwardly and upwardly from the shaft 22 and another similar shaft 37, respectively. The cylinder 34 is open at its bottom and has a piston 38 operating therein. The piston is connected through a link 39 with the outer end of a lever 40 fixed to the gear box 10 so as to be rigidly attached to the combing wheel. Con-

sequently, raising of the piston 38 lowers the combing wheel.

The upper closed end of the cylinder has a vertical suction port 41 connecting the cylinder with a constant source of suction (not shown) through a suction line 42. This upper closed end of the piston also has a horizontal bore 43 intersecting the port 41, which bore is connected with the source of suction which is applied at the suction cup through a fitting 44 and a suction line 45.

Slidably in the bore 43 is a valve 46. The valve 46 is substantially spool-shaped and is yieldingly held by a spring 47 against an adjustable stop 48 in a position at which its reduced medial portion is in alignment with the port 41. The adjustable stop 48 is threaded in a plug 49 which closes the outer end of the bore 43 and the spring 47 is confined between the opposite end of the valve 46 and the inner end of the bore 43.

An air bleed 50 also extends through the closed upper end of the cylinder, preferably parallel to the port 41 and intersected by the bore 43. The location of this air bleed with respect to the dimensions of the valve 46 is such that when the valve is in its normal position to which it is urged by the spring 47, the air bleed is closed.

Operation

In operation, a constant suction is applied at the port 41 through the suction line 42 and suction is periodically applied to the suction cup, and consequently, the inner end of the bore 43 under control of the cam controlled timing valve 18. The functioning of this valve is coordinated directly with the raising and lowering of the suction cup so that when the suction cup is lowered toward the top of the pile, the valve is open and suction is present and upon being lifted, the valve is closed to cut off the suction and release the sheet.

There being a constant suction applied at the port 41, it follows that as long as this port is open, the piston 38 will tend to respond and lower the combing wheel onto the pile of sheets. However, this tendency on the part of the piston 38 to lower the combing wheel is positively opposed by the connection between the combing wheel and the suction cup so that the combing wheel moves into engagement with the pile of sheets only as the suction cup and presser foot 11 are lowered. The disposition of these elements in operative relation to the pile of sheets is substantially concurrent.

Immediately upon the engagement of the combing wheel with the top of the pile, the topmost sheets are buckled. As the topmost sheet engages the mouth of the suction cup and seals it, the entire effect of the suction in this line is applied on the valve 46 which, consequently, is drawn to the left against the spring 47 to a position closing the port 41 and uncovering the air bleed 50. This disconnection of the cylinder from the constant suction source immediately releases the combing wheel to be lifted by its spring 27 so that the contact of the combing wheel with the sheets is only long enough to effect the sealing of the suction cup.

From the foregoing description taken in connection with the accompanying drawings, it will be readily apparent to those skilled in the art, that this invention provides a sheet separator so constructed as to be conducive to high speed operation and in which the period of contact be-

tween the combing wheel and paper is reduced to a minimum.

What I claim as my invention is:

- 5 1. In a sheet separator: a combing wheel operatively engageable with the top of a plurality of sheets to buckle the same; a suction cup for engaging the topmost sheet at its buckled portion; positively driven means for raising and lowering the suction cup; yieldable means tending at all 10 times to lift the combing wheel off the sheets; pneumatic means for lowering the combing wheel onto the sheets; and valve means responsive to the sealing of the suction cup by the topmost sheet for rendering said last named pneumatic 15 means inoperative so that the sealing of the suction cup by the topmost sheet is accompanied by immediate lifting of the combing wheel.
- 20 2. In a sheet separator, the combination of: a combing wheel biased to raised position; suction responsive means for lowering the combing wheel onto the topmost of a plurality of sheets to buckle the same; a suction cup for engaging the topmost sheet at its buckled portion; and means responsive to the sealing of the suction cup by the 25 topmost sheet for rendering said suction responsive means inoperative so that the sealing of the suction cup by the topmost sheet is accompanied by immediate raising of the combing wheel.
- 30 3. In a sheet separator: a combing wheel adapted to engage the topmost of a plurality of sheets to buckle the same; a suction cup for engaging the topmost sheet at its buckled portion; means responsive to suction for lowering the combing wheel into operative engagement with the topmost sheet; means for connecting the suction responsive means with a constant source of suction; and means responsive to the sealing of the suction cup for disconnecting said suction responsive means from its suction source.
- 40 4. A sheet separator: a combing wheel to buckle the topmost of a plurality of sheets; a suction cup for engaging the topmost sheet; means for yieldingly holding the combing wheel off the sheets; means responsive to suction for lowering the combing wheel onto the topmost sheet; means for connecting said suction responsive means with a constant source of suction; means for connecting the suction cup with a source of suction; and means responsive to the suction applied at the 45 suction cup and operable upon sealing of the suction cup for disconnecting the first named suction responsive means from its suction source.
- 50 5. In a sheet separator, the combination of: a combing wheel movable to and from operative engagement with a plurality of sheets; a suction cup adapted to pick up one sheet from said plurality; means yieldingly holding the combing wheel off the sheets; a constant source of suction; means responsive to said constant suction for 55 engaging the combing wheel with the sheets; means for providing suction at the suction cup; a valve responsive to the suction applied at the suction cup for disconnecting said first named suction responsive means from its source of constant suction to free the combing wheel for movement out of engagement with the sheets; and a spring holding said valve in an inoperative position as long as the suction cup is open.
- 60 6. In a sheet separator: a combing wheel movable to and from operative engagement with a plurality of sheets to buckle the same; a suction cup engageable with the topmost sheet; a spring tending at all times to move the combing wheel out of engagement with the sheets; pneumatic means acting in opposition to said yielding means
- 65 for moving the combing wheel into operative engagement with the sheets; means for providing suction at the suction cup; and a valve responsive to the suction applied at the suction cup upon sealing of the suction cup for rendering said pneumatic means inoperative to release the combing wheel for its spring actuated movement.
- 70 7. In a sheet separator: a combing wheel; means mounting the combing wheel for movement to and from engagement with the topmost of a plurality of sheets; a suction cup adapted to engage the topmost sheet; a spring tending at all times to lift the combing wheel off the sheets; a cylinder; a piston movable in the cylinder and connected with the combing wheel to lower the same upon motion of the piston in one direction; a suction line connected with the cylinder to evacuate the same and cause motion of the piston in said direction; means for producing a suction at the suction cup; and a valve responsive to the suction applied at the suction cup upon sealing of the suction cup for disconnecting the cylinder from said suction line so that the engagement of the sheet with the suction cup is accompanied by immediate lifting of the combing wheel.
- 75 8. In a sheet separator: a combing wheel adapted to be lowered onto the topmost of a pile of sheets and biased to a raised inoperative position; a suction cup; positive means for raising and lowering the suction cup; constantly operative pneumatic means tending to lower the combing wheel into operative relation with the topmost sheet; a connection between the combing wheel and the suction cup to coordinate the lowering of the combing wheel and suction cup, said connection allowing for the lifting of the combing wheel independently of the suction cup; and means operable upon the sealing of the suction cup for disconnecting the combing wheel from said constantly operative pneumatic means to instantly release the combing wheel for movement to a raised position.
- 80 9. In a sheet separator: a combing wheel; means mounting the combing wheel to oscillate about a fixed axis to and from operative engagement with the topmost of a pile of sheets; a suction cup; means mounting the suction cup for movement toward and from the top of the pile of sheets; a spring yieldingly tending to lift the combing wheel off the top of the pile of sheets; pneumatic means to oppose the spring and lower the combing wheel into operative engagement with the top of the pile of sheets; positive means for raising and lowering the suction cup; a lost motion connection between the suction cup and the combing wheel to insure simultaneous lowering of the same while permitting the combing wheel to be lifted independently of the suction cup; and means operable upon sealing of the suction cup for disconnecting the combing wheel from its pneumatic actuating means to release the same for immediate lifting by said spring.
- 85 10. In a sheet separator: a combing wheel movable to and from operative engagement with the top of a pile of sheets; a suction cup movable toward and from the top of the pile of sheets; a presser foot movable with the suction cup and so disposed with respect to the suction cup and combing wheel that the suction cup is positioned between the presser foot and combing wheel so that sheets buckled between the presser foot and combing wheel are moved upwardly toward the mouth of the suction cup; positive means for raising and lowering the suction cup and presser

- foot; a spring at all times tending to lift the
combing wheel off the pile of sheets; pneumatic
means connected with the combing wheel and
operable in opposition to the spring for lowering
5 the combing wheel onto the pile of sheets; a lost
motion connection between the combing wheel
and the connected suction cup and presser foot
to insure simultaneous lowering of the suction
cup, presser foot and combing wheel while en-
10 abling independent lifting of the combing wheel;
means for providing suction at the suction cup;
and means responsive to the suction applied at
the suction cup upon sealing of the suction cup
for rendering the pneumatic means inoperative
15 to release the combing wheel for immediate lift-
ing by its spring.
11. In a sheet separator: a combing wheel
adapted to engage the topmost of a pile of sheets
to buckle the same; a suction cup for engaging
20 the topmost sheet at its buckled portion; pneu-
matic means for holding the combing wheel
against the topmost sheet of said pile; and means
responsive to the sealing of the suction cup by
the topmost sheet for rendering said pneumatic
25 means inoperative.

12. In a sheet separator: a combing wheel
adapted to engage the topmost of a pile of sheets
to buckle the same; a suction cup for engaging
the topmost sheet at its buckled portion; pneu-
matic means for lowering the combing wheel onto
5 the sheets and for holding the combing wheel
against the topmost sheet of said pile; and means
responsive to the sealing of the suction cup by
the topmost sheet for rendering said pneumatic
means inoperative.

10

13. In a sheet separator: a combing wheel;
means for biasing the combing wheel to raised
position; pneumatic means acting in opposition
to said biasing means for lowering the combing
wheel onto the topmost of a pile of sheets and
15 for holding the wheel thereon to buckle the top-
most sheet; a suction cup for engaging the top-
most sheet at its buckled portion; and means re-
sponsive to the sealing of the suction cup by the
topmost sheet for rendering said pneumatic
20 means inoperative so that the sealing of the suc-
tion cup by the topmost sheet is accompanied by
immediate raising of the combing wheel.

FRANK R. BELLUCHE. 25
